RECTIFIER OF HEAVY ELECTRIC CURRENTS

Paul Wangemann, Berlin, Germany

Application May 1, 1936, Serial No. 77,446
In Germany November 14, 1935

16 Claims. (Cl. 175—364)

In order to rectify heavy electric currents running sometimes even up to several thousands of amperes, the interruption must be made fifty times per second according to the usual frequency of the alternating or multiphase currents. This is possible, only if the switching-off is made without the slightest spark, because the light arc cannot be extinguished as quickly as the frequency of the current demands it. According to 5 my invention, to rectify such enormous currents with the usual frequency an electrolytic jet is used, which bridges the space between two electrodes, at least one element being movable preferably rotatably. For rectifying purposes the 10 switching is made preferably without voltage jump. In using an electrolytic jet, there must be no metallic contact between the electrodes at the point of interruption, that is to say, inside the electrolyte, to avoid any light arc or spark. 15 In case the process or apparatus is to be used also for regulating or starting purposes, a voltage jump cannot be avoided. In this case the cathode should always be covered by the electrolyte, so that the cathode spot shall not be formed on 20 metal.

The formation of an arc is due to metallic vapours at the point of interruption. The arc is avoided when, at the point of interruption, no 25 metals are present which owing to the cathode's spot might evaporate, and when, during the brief process of switching off, less resistance is offered to the migration of the ions through the conductor of the second class than to the migration of the electrons in the arc between the electrodes. 30 First class conductors are those with a positive temperature coefficient of resistance, for instance metals including mercury. Second class conductors are those with a negative temperature coefficient, for instance electrolytes.

40 Mercury interrupters are known. Mercury, however, as a metal, is a conductor of the first class. Therefore, when the slightest current is interrupted with the aid of mercury, sparking cannot be avoided, because metallic vapour will 45 always be formed at the points of interruption, quite apart from the fact that in the case of metals, any distinction between anode and cathode would be superfluous so far as the principle of the present invention is concerned. It is believed to be quite impossible to switch several 50 thousands amperes fifty times per second by the aid of mercury.

In the case of the sparkless system of interruption according to my invention direct current 55 as well as alternating current, coincident phase

and displaced phase can be switched off and owing to the sparkless interruption even repeatedly in the very briefest of intervals, for example, with the frequency of 50 periods per second, so that this sparkless interruption can be used with 5 special advantage for heavy current rectifiers, motor and generator commutators and spasmodic regulators, for example, for the starting of motors.

In the following remarks, jet conductors of the second class are understood, even though only 10 electrolytes, electrolytic jets, or even only briefly jets or liquid jets are mentioned.

The forms of construction, by way of example of the invention, are shown diagrammatically in 15 the accompanying drawings, in which—

Fig. 1 is a horizontal sectional view through a circuit breaker for multi-switching.

Fig. 1a is a partial illustration showing a 20 modification of the embodiment shown in Fig. 1.

Fig. 2 is a similar view through a form of the invention designed for rectifying purposes and showing the electrical connections therefor.

Fig. 3 is a vertical sectional view of the rectifier 25 shown in Fig. 2.

Fig. 4 is a vertical sectional view of a modified form of rectifier.

Fig. 5 is a horizontal sectional view of the 30 rectifier shown in Fig. 4, partly broken away.

Figs. 6 to 14 are detail views of parts of the 35 rectifier, shown in Fig. 4 according to several modifications.

Fig. 15 is a vertical sectional view of a modified form of a three-phase rectifier with one electrolyte tank for each phase.

Figs. 16 and 17 are voltage diagrams.

Referring to the drawings in detail and in particular to Fig. 1, the numeral 3 indicates a container for the electrolyte 4, the container being in the form of a cylinder with a vertical axis. 40 An insulating cylinder 5 is rotatably mounted concentrically with the axis of the container 3. A series of stationary electrodes 2—2^v are secured in an annular group to the wall of the container 3 above the level of the electrolyte with the operative faces thereof in close proximity to the surface of the insulating cylinder 5. Stationary electrodes 1—1^v are arranged within the insulating cylinder 5 and are in the form of nozzles, through which the electrolyte is forced in 45 the form of a jet towards the respective outside electrodes 2—2^v. The insulating cylinder or drum 5 is formed with a slot 9 which, as said cylinder is rotated, successively uncovers one of the several nozzle-like electrodes 1 and permits the jet 50

of electrolyte issuing therefrom to impinge upon the adjacent phase electrode 2-2^v and thereby complete the electrical connection between these electrodes and for a brief period, the electrolyte 5 returning by gravity to the bottom of the container 3 and the jet being interrupted by the trailing edge of the slot 9 as the rotary movement of the insulating cylinder continues.

A circuit breaker of this type is capable of use 10 as a rectifier and in this case the outside electrodes 2-2^v insulated from each other are connected with the individual phases of the multi-phase alternating current. The width of the slot 9 determines the duration of the circuit closing 15 period between the pairs of electrodes 1 and 2 and preferably the width of said slot is such that for a brief moment, two jets from the nozzle-like electrodes 1-1^v contact simultaneously with the related electrodes 2-2^v so that the switching- 20 over from one phase to another is effected without jump of voltage or interruption of current as indicated in the diagram in Fig. 16 hereinafter more fully described.

The slot 9 can be closed by a metal plate 9' as 25 shown on the partial diagram according to Figure 1a. In this case also each of the outside electrodes 2-2^v forms a nozzle and ejects an electrolyte jet. When the jets of the electrodes 1 and the jets of the electrodes 2, beat at the same time 30 the metal plate 9' inserted in the slot 9, the circuit is closed. It is possible to avoid the metal plate. In this case the two jets of the electrodes 1'' and 2'' collide, but the metal plate has the advantage that the jets flow more smoothly. 35 It will be noticed that in the arrangement illustrated the phase electrodes 2-2^v are widely spaced apart and being adequately insulated, the arrangement is particularly advantageous for the rectification of alternating currents of very high 40 voltage.

Referring to the arrangement shown in Fig. 2 a system of connections for multi-phase rectification is illustrated in combination with a modified form of circuit breaker. In place of the slotted 45 insulating cylinder shown in Fig. 1, a rotating electrolytic jet is used as the contact maker. As in the case of the arrangement shown in Fig. 1 the nozzle-like electrode 1^a rotates in synchronism with the alternating current supply. In order to reduce the number of revolutions required for rectifying purposes, a double number 50 of poles can be employed.

As shown in Fig. 2 on the three-phase alternating current side, the ends 12 of the windings of 55 a transformer are connected to the related electrodes 2^a and the neutral point 13 of the transformer or another artificial neutral point of the system forms one direct current pole while the rotating nozzle-like electrode 1^a and the jet of electrolyte discharged therefrom forms the other direct current pole.

The nozzle-like electrode 1^a for the electrolyte jet is preferably the cathode and electrode 2^a the anode. In this case the electrolytic jet discharged from the nozzle-like electrode 1^a covers the cathode so that the formation of the cathode spot is avoided. The liquid jet will therefore move in a direction opposite to that of the electric current which flows from the electrode 2^a to 65 the electrode 1^a.

As shown in Fig. 3 a synchronous motor 14 is provided for rotating the nozzle-like electrode 1^a and the latter is extended downwardly below the level of the electrolyte 4 in the container 3 and 70 the open end thereof is so disposed that, during

rotation, the electrolyte is forced upwardly through the hollow electrode 1^a and discharged from the upper nozzle-like portions thereof.

In order to avoid creeping currents due to the electrolyte dripping from the electrodes 2^a the vessel is preferably provided with an air ring 3'. It will be noted that the construction shown in Fig. 1 differs from that disclosed in Figs. 2 and 3 only insofar that in the case of Fig. 1 a slotted insulating drum rotates in front of as many stationary nozzle-like electrodes 1-1^v as there are phase electrodes, whereas in the form of construction in Figs. 2 and 3 only one or one pair of nozzles is provided without the insulating drum.

One of the most important advantages of the 15 present rectifier system consists in that no slip rings are required. The phase electrodes are stationary and are connected with fixed cables. According to the arrangement shown in Fig. 1 the nozzle-like electrodes are also stationary and are 20 similarly connected to fixed cables, whereas in the case of rectifiers with a rotating nozzle-like electrode 1^a, the current is conducted from the bottom of the container 3 by means of cable connection 15 and the electrodes 2^a are positioned 25 above and out of contact with the body of the electrolyte.

According to the arrangement shown in Figs. 4 and 5, the electrodes 2^b are arranged in a horizontal plane and the nozzle-like electrode 1^b is correspondingly arranged. The rotor 16 is rotatable around a vertical axis and is constituted by a hollow cone the lower open end which is immersed in the electrolyte 4^b in the bottom of the container 3^b and the upper end thereof is in communication 35 with head 16'. The nozzle-like electrode 1^b is in communication with the head 16' and during rotation of the cone 16, the electrolyte is raised by suction entering the head 16', thus flows outwardly and downwardly through the open nozzle without appreciable pressure.

The fixed electrodes 2^b are preferably formed of ring sections having wedge-shaped cross sections, the members of each electrode being held in spaced relation by suitable spacing members 45 as shown in Fig. 6. The individual electrodes 2^b are of arcuate form and separated by radial slots 18. These electrodes 2^b are fastened to the cover of the vessel 3^b by means of insulating brackets 19.

The container cover also carries the motor 14^b the rotor 16 with the head 16' and nozzle 1^b by means of the bearing arm 20 whereby the mutual adjustment of the electrodes 1^b and 2^b can be effected when these parts are removed from the 55 vessel as a unit with the cover.

The advantage of this design of the electrodes 1^b and 2^b lies in the fact that the electrolyte jet passes tangentially through the wedge-shaped members 21 in the nozzle-like electrode 1^b and 60 flows tangentially downwards around the wedge-shaped ring segments of the electrode 2^b. In this way it is possible to greatly increase the area of contact surface between the electrode and electrolyte, to regulate the thickness of the electrolytic jet by raising the rotor 16 vertically and entirely avoiding the electrolyte becoming atomized by striking against the electrodes 2^b, owing to the fact that the jet, in this case, is not subjected to appreciable pressure which might tend to produce an atomizing effect.

Fig. 7 shows in section a modified form of the nozzle 1^c and the stationary electrode 2^c. The rotating electrode 1^c has wedge-shaped members or liners 21 and 21' tapering off towards the top. 75

The liners 21' engage between the stationary rings of the electrode 2^c. The liners 21 lie opposite those stationary rings of the electrode 2^c, so that the electrolyte can pass over without eddies. In this arrangement it is immaterial whether the tongues of the liners 21' which engage between the rings of the stationary electrodes 2^c taper off downwards or are parallel. An insulating apron 26, one for each phase, deflects the liquid preferably to the wall of the container 3^c.

If the circuit breaker is used for rectifying purposes a jump of voltage should be avoided if the jet of the electrode 1^d pass over from one electrode 2^d to the next one as shown in Fig. 8.

Fig. 16 shows a diagram of the voltage of the different phases I, II, III, IV, V, VI. The part I from a to (a) is cut out by the electrolytic jet touching one electrode. The electrolytic jet 20 should pass over to the next electrode 2^d in Fig. 8 in the moment where the voltages of phase I and phase II are the same. In this case the passing over of the electrolytic contact from phase I to phase II is done without a jump of voltage. If 25 the electrolytic jet leaves the left electrode 2^d in Fig. 8 before the electrolytic jet reaches the right electrode 2^d the current is completely interrupted till the electrolytic jet reaches the right electrode 2^d. This current interruption and the voltage 30 jump should be avoided in any case.

On the other hand, the common contact between the electrolytic jet and the left and the right electrode 2^d should not last too long a time because in the next moment the voltage of the 35 phase II is increased while the voltage of phase one is diminished so that by the common contact between the electrode of the phase I and II short circuited currents would arise. The joint contact of the phase electrodes I, II, III should not be 40 longer than 2 or 3 angle degrees. For this reason the electrolytic jet from the nozzle electrode 1^d is wider than the slot 18 in Fig. 8. To avoid a longer short circuit between the subsequent phase electrodes it is important that the electrolytic 45 jet is ejected straight out avoiding a curved flag of the electrolytic jet at the outlet of the rotating nozzle. The contour of the flag is shown in Fig. 9. The most effective means, however, is to use a jet of compressed air which deflects the 50 freely emerging liquid jet with strong air pressure as soon as it has left the tongues 21 of the nozzle. In Fig. 11 the mouth of the tube for the compressed air is denoted by 31 and is at right angles to the direction in which the emerging 55 jet of the electrolyte moves, so that the jet 30 of liquid is deflected in the direction of this jet of compressed air without the stationary electrodes being touched further by it. In Fig. 12 the compressed air nozzle rotates with the electrolyte 60 nozzle 1^d. For this purpose a Pitot tube 36 is mounted on the rotating nozzle 1^d and opens into the air pressure nozzle 33, which passes behind the emerging jet 30 of liquid. In front in the direction of motion the Pitot tube has the mouth-piece 42. The direction of the jet may also be 65 assisted by arranging a suction device 34 with an injector nozzle 35 in front of the jet. In Fig. 13 the jet nozzle 1^d with the rotor 38 is shown in side elevation. The rotor may consist of a forked tube 31, 38 which may be closed by a foot valve 40. The forked piece 37 may be advantageously 70 sloped, so that the surface of the liquid remains at the level 39. At the commencement of the rotation this quantity of the electrolyte will be centrifugally projected outwards and will instantly

create suction. The individual phase apron 26 of the Fig. 7 can be fixed as 26' on the rotor so that it is always underneath the nozzle 1^d and receives the emerging jet, especially if in the rotating apron 26' a suction effect is produced. Instead of the ball valve 40 in the rotating tube 38 the tube 40 may be stationary and surround a rotating conveyor screw, which is driven by the rotating part 37 inside the collar of the stationary tube 42 of Fig. 14. Instead of only one rotating nozzle 1 a rotating nozzle 1^e in tanks 3^e insulated from each other is provided in Fig. 15 for each phase. This construction is adapted especially for the rectifying of high voltage currents. It is obvious, that in this construction the emerging 15 "flag" of this jet may be rendered innocuous by the space between the single electrodes 2^a, by using different liquid tanks for the several stationary electrodes of different phases are shown in Fig. 15.

If the rectifier is to be used at the same time as a starter, the electrodes 2^b may be tapered radially and inwardly as shown in Fig. 5. In this case, by means of a suitable deflection, not shown, of the electrolytic jet, the current is interrupted 20 for a considerable period during the moment it passes over from one electrode to the other. The circuit closing periods are at first brief and increase gradually as the jet is deflected outwardly until the closure period remains uninterrupted 25 as when the jet assumes the position shown in Fig. 4. Vertical electrodes 2^a have their tapered part above or below the normal position of the rotor which is then displaced in height, as shown in Fig. 3.

For operation, two points are important, first, the deaeration of the vessel 3^b in order to carry off the products of electrolysis. For this purpose the rotor 16 is provided with a ventilating device 22 preferably mounted on the circumference 40 thereof and which draws air out of the openings 23 through electrode slots 2^b and forces it upwardly through the air vents 24. The second important point is the heat regulation of the electrolyte 4^b. Conductors of the second class 45 have a negative temperature coefficient which is many times that of the temperature coefficient of metal, consequently the internal resistance will diminish considerably when the temperature is increased and at 90° it will be down to half, relatively to the resistance of the temperature of the air, the degree of efficiency will accordingly increase very considerably if the temperature is kept at a temperature of a few degrees below 100.

The regulation of the temperature is most readily effected by means of a heat protective and insulating jacket 25 which at the top or at the bottom is formed with a bent edge 25' so that the current of air flowing between the vessel 3^b and the jacket 25 may be regulated by raising or lowering said jacket. Under the electrodes 2^b, a cone-shaped insulating ring 26 is mounted which deflects the electrolyte jet towards the wall of the container 3^b and allows it to drip downwardly. At the same time the ring serves to change the 55 direction of the fresh air supplied by the openings 23.

The regulation of the average current at a constant voltage is afforded by the tapering of the anodes 2^a and 2^b toward the center but even 70 without any interruption of the current, the voltage may also be regulated, for example, for the purpose of starting motors. Fig. 16 illustrates the normal course of the voltage with six impulses of very low amplitude in the case of a 75

three-phase alternating current. If, however, as shown in Fig. 17, the nozzle 27 is turned in phase relatively to the phase coincidence synchronism, a diminution of the voltage can be produced. If 5 two nozzles 27 and 28 in two vessels separated one from the other is used, the voltage curve 29 is obtained. If, on the other hand, the nozzle 28 is turned relatively to the nozzle 27 through an angle, for example, of 60°, the voltage curve 30 will be attained. If now we call the angle enclosed by the two nozzles 180°- α , the best possible curve will be obtained when the nozzle 27 is turned back through $\alpha/2$ and the nozzle 28 through $3\alpha/2$. By mechanical means the ratio 10 1:3 may be attained by displacing the casing of the synchronous motors by means of worm wheels. This displacement can also be attained by electrical means by super-exciting the synchronous motors. In this case the same shape of 15 curve as that at full voltage can be obtained. One single jet contact in only one vessel will suffice, but in this case the voltage curve will be distorted but nevertheless will be continuous. During the brief moment of starting, however, 20 25 the distortion of the voltage curve is not of consequence.

What I claim is:

1. In a device for sparklessly rectifying heavy electric currents, a polyphase current supply system, stationary phase electrodes in fixed connection with the phase lines, at least one nozzle electrode constituting a direct current pole, said nozzle electrode being adapted to discharge an electrolytic jet into contact with the phase electrodes. 30
2. In a device for sparklessly rectifying heavy electric currents, a polyphase current supply system, at least one synchronously rotatable electrolytic jet, a nozzle for the said jet constituting one cathode, and stationary phase electrodes connected with said system, the said stationary phase electrodes being touched by the said electrolytic jet and constituting the anodes. 35
3. In a device for sparklessly rectifying heavy electric currents, at least one electrolytic jet, electrodes, at least one of said electrodes forming a synchronously rotatable nozzle for the said electrolytic jet adapted to constitute a contact between a series of other of said electrodes, a container for the electrolyte for supplying the electrolytic jet, the said nozzle being sloped forwardly in the direction of rotation. 40
4. In a device for sparklessly rectifying heavy electric currents, at least one electrolytic jet, electrodes, at least one of the said electrodes forming a synchronously rotating nozzle for the said electrolytic jet adapted to constitute a connection between the nozzle electrode and a series of other said electrodes, a container for an electrolyte for supplying the electrolytic jet, and 45 means rotating synchronously with the said nozzle electrode for collecting and deflecting the electrolytic jet after its passage over the electrodes of said series.
5. In a device for sparklessly rectifying heavy electric currents, at least one electrolytic jet, one electrode forming a nozzle for the said electrolytic jet adapted to constitute a connection between the nozzle electrode and the other electrodes, and means for regulating the temperature of the electrolyte. 50
6. In a device for sparklessly rectifying heavy electric currents, at least one electrolytic jet, electrodes, at least one of said electrodes forming a synchronously rotatable nozzle for the said electrolytic jet adapted to constitute a connection be- 55

tween a series of other of said electrodes, the said electrodes being so spaced that the said electrolytic jet is adapted to touch simultaneously two adjacent electrodes.

7. In a device for sparklessly rectifying heavy 5 alternating electric currents, at least one electrolytic jet, electrodes, at least one of the said electrodes forming a synchronously rotating nozzle for the said electrolytic jet adapted to constitute a connection between the nozzle electrode 10 and a series of other of said electrodes, and means for regulating the direct current voltage by displacing the said synchronously rotating nozzle out of phase coincidence relation to the alternating current system. 15

8. In a device for sparklessly rectifying heavy electric currents, electrodes, at least one electrolytic jet adapted to constitute a connection between two opposite electrodes and means adapted to guide the electrolytic jet tangentially 20 along the said electrodes.

9. In a device for sparklessly rectifying heavy electric currents, electrodes, at least one electrolytic jet, adapted to constitute a connection between the said electrodes, said electrodes having partition walls adapted to guide the electrolytic jet parallel to the said partition walls from the nozzle electrode to the touched electrode. 25

10. In a device for sparklessly rectifying heavy electric currents, electrodes, at least one electrolytic jet, adapted to constitute a connection between the said electrodes, the said electrodes having interspersed partition walls adapted to guide tangentially the electrolytic jet between the electrodes. 30

11. In a device for sparklessly rectifying heavy electric currents, electrodes, at least one electrolytic jet, adapted to constitute a connection between the said electrodes, the said electrodes having interspersed partition walls adapted to guide 40 the electrolyte while crossing the space between the said partition walls. 45

12. In a device for sparklessly rectifying heavy electric currents, electrodes, at least one electrolytic jet, adapted to constitute a connection between the said electrodes, having partition walls composed of conducting segments separated by spacing pieces. 50

13. In a device for sparklessly rectifying heavy electric currents, at least one electrolytic jet, electrodes, one of said electrodes forming a nozzle for the said electrolytic jet adapted to constitute a connection between the said nozzle electrode and another touched electrode, and means adapted to adjust the nozzle electrode axially relative 55 to the touched electrode.

14. In a device for sparklessly rectifying heavy alternating currents, electrodes spaced from each other and connected to the respective alternating current lines, a nozzle electrode for an electrolytic jet, said jet being adapted to touch one of said spaced electrodes after another in synchronism with the alternating current supply and to touch two of said spaced electrodes simultaneously while switching over from one touched electrode to the next one, the nozzle electrode constituting the cathode and the touched electrodes the anodes. 60

15. In a device for sparklessly rectifying heavy alternating currents, a plurality of nozzles for electrolytic jets, electrodes connected to the respective alternating current lines, and means for causing said electrolytic jets to touch their respective line electrodes periodically in synchronism with the alternating current supply, each 70

line electrode and its co-acting nozzle and jet being contained in a separate container.

16. In a device for sparklessly rectifying heavy electric currents, a container, an electrolyte therein, means for producing at least one electrolytic jet, electrodes, one of said electrodes forming a rotating nozzle for said electrolytic jet adapted to constitute a connection between the

nozzle electrode and another touched electrode, means adapted to adjust the nozzle electrode axially relative to the touched electrode, said nozzle electrode comprising a central tube immersed in said electrolyte, and means to lift continuously the electrolyte from the bottom of said container to said nozzle.

PAUL WANGEMANN.
